COVER TUCKING MECHANISM FOR MATCH BOOKING MACHINES

Charles F. Wright, Akron, Ohio, assignor to The Diamond Match Company, New York, N. Y., a corporation of Delaware

Application May 4, 1939, Serial No. 271,741

5 Claims. (Cl. 93—2)

This invention relates to match booking machines, having reference more especially to a type of booking machine equipped with means for closing the match book covers preparatory to the discharge of the finished books. A machine of this type is illustrated in Patent No. 1,042,472 dated October 29, 1912, wherein the closing means comprises a bed or shelf upon which the match books, face upward, are imposed in succeeding order, the face of each book embodying a foldable cover flap and an end retaining fold therefor. Overhanging the bed or shelf is a four-motion friction element which co-acts with the flap of each succeeding book in a manner to tuck the free end of the flap under the retaining fold.

In closing the flexible cover flaps, particularly when varnished cover material is employed, considerable trouble has been experienced on account of the curling or distortion of the flaps while their ends are being forced under the retaining folds of the respective match books by means of the previous tucking mechanisms.

To overcome this objection is the object of my invention, and to that end I have provided the tucker element with simple and efficient flap guiding means which, in a preferred form, will be hereinafter described; the scope of the invention being expressed in the appended claims.

In the drawings—

Figure 1 is an elevation of the delivery end of a match booking machine provided with a tucker element embodying my invention, the tucker being shown in its forward downward position at the completion of the tucking motion and the closed book being indicated as supported in its holder under the acting end of the tucker.

Fig. 2 is a transverse vertical section through the book support and the adjacent tucker foot.

Fig. 3 is a bottom view of a tucker foot.

Fig. 4 is a sectional end elevation of the companion book supports and the tucker feet in co-operative relation thereto, the feet being shown in raised position in respect to the match books.

Fig. 5 is a similar view showing the tuckers in down or acting position.

Fig. 6 is a horizontal section, as on the line 6—6 of Fig. 5.

Fig. 7 is a perspective view of one of the elastic base pads of a book holder.

Referring to the drawings, 10 designates a portion of the main frame at the delivery end of a match booking machine of the type referred to, and 11 designates an intermittently movable chain of book carrying links from which, in the present

instance, succeeding pairs of books with outwardly extending closure flaps are ejected by means of a horizontally reciprocating plunger 12.

13 designates an intermittently movable wheel which is located adjacent the path of the chain and is mounted to rotate in bearings on rearwardly extending brackets 14 bolted to the main frame. Formed in and around the periphery of the wheel are equally spaced pairs of radial pockets 15 into each succeeding pair of which in a dwell of the wheel the ejected books (B) are inserted by the action of the plunger 12, the closure flaps (f) of the respective books thus inserted extending outwardly from the wheel. Overlying the upper semi-circular path of the wheel are spaced flap-bending members 16 which terminate in rearward resilient extensions 17 overhanging a pair of counterpart book holders 18 which are supported by the main frame and are provided with upwardly and rearwardly inclined spring bottom plates 19, as usual. The cover flaps of each succeeding pair of books in their intermittent travel to the extension are angularly flexed and then, while the wheel is at rest, the books are endwise ejected from the pockets of the wheel by the action of a reciprocating plunger 20. This plunger advances the successive pairs of books beneath the extensions 17 in a manner to effect the folding of the respective flaps flatwise upon the contained matches, and at the same time the leading books are positioned in the respective book holders. The books are discharged in pairs from the wheel 13 in similar endwise and face arrangement, the larger or headed ends of the matches leading and the fold flaps of the covers being upward.

As herein illustrated the book holders 18 include suitably-spaced slotted walls 21 and a base member 22 therefor, the whole supported by a bed 23 extending rearwardly from the brackets 14. The inclined plates 19 are secured at their lower ends to the bed and the higher or free ends of the plates extend into the respective holders so as to afford a resilient support for the match books introduced in the holders.

Overhanging the wheel 13 is a four-motion tucker arm 24 having a downwardly extending bifurcated portion 25 carrying friction blocks 26, preferably of rubber, in proximity to the flaps of the match books which are seated in the holders. The blocks 26 by actuation of the tucker arm are effective to bear upon the underlying folded cover flaps (f) of each succeeding pair of books and tuck the free ends of the flaps under the retain-

ing folds (a) at the narrow ends of the respective books.

Mechanism such as shown in Patent No. 1,042,472 may be employed to reciprocate the arm 24 lengthwise and at determined intervals in its reciprocation to effect the rising and permit the falling motion of the arm relatively to the cover flap. In the present instance the means for effecting the vertical motion of the arm 24 includes a reciprocative lifter bar 27 which suitably supports the arm adjacent its bifurcated portion.

In Patent No. 1,042,472 aforesaid the lower end of each of the limbs 25 of the bifurcated tucker arm supports the friction block 26 which centrally acts upon the underlying flap, but as hereinbefore mentioned the curling tendency of the cover material, particularly when varnished, may impair the efficiency of the tucking operation.

According to my present invention I provide each of the tucker limbs with spaced friction members arranged and adapted to be brought in close contact with the opposing longitudinal edges of the underlying cover flap when the central friction member is lowered, thus remaining during the tucking stroke and obviating liability of the upward curling of the edges of the flap.

In the present instance the foot of each of the tucker limbs 25 is provided with a horizontal cross-bar 28 having depending end members 29, which bar overhangs the adjacent book holder. On the underside of the bar midway between its ends is a fixed rib 30 to which is secured the depending friction block 26, which is preferably of rubber. Fastened to the inner sides of the respective end members 29 are friction blocks 31, also preferably of rubber, having depending portions which are downwardly and outwardly bevelled on their inner faces, as at 32, such faces being so disposed as to embrace the opposing edges of the proximate cover flap coincidentally with the impact of the central block 26 on the flaps, as seen in Fig. 5. Thus it will be seen the bevelled faces of the blocks 31 not only tend to deflect the opposing edges of the flap slightly downward as indicated, but they also co-act with the central block to impart a positive and uniform tucking motion to the flap.

I preferably mount in the bottom of each book holder 18 a pair of elongated friction pads 33, preferably of rubber, which are constructed and arranged to register with apertures 34 in the resilient book supporting plate 19 when the plate is depressed by the book during the tucking operation. The pads 33 present to the opposing surface of the book cover a plurality of relatively large friction areas which obviate displacement of the book without marring the surface.

As herein shown the vertical sides of the elastic pads are longitudinally grooved, as at 35, and the upper surface of the base 22 is provided with parallel under-cut slots 36 which receive the respective pads and interlock with the grooves of the latter, as clearly seen in Figs. 4 and 5. Thus the pads can be readily mounted on or detached from the base, as occasion may require.

I claim—

1. The combination of means for supporting a match book having an open cover flap and a retaining portion for the free end of the flap, and a tucking element overhanging said supporting means and having a longitudinal and vertical motion relatively to the flap of an underlying book, said element including pressure means thereon which bear against the body and at least one of the longitudinal edges of the opposing flap of said book during the effective motion of said element.

2. The combination of means for supporting a match book having an open cover flap and a retaining portion for the free end of the flap, and a tucking element overhanging said supporting means and having a longitudinal and vertical motion relatively to the flap of an underlying book, said element including depending pressure members arranged in spaced relation to bear against the body and the longitudinal edges of the opposing flap of said book during the effective motion of said element.

3. The combination of means for supporting a match book having an open cover flap and a retaining portion for the free end of the flap, and a tucking element overhanging said supporting means and having a longitudinal and vertical motion relatively to the flap of an underlying book, said element including depending members having oppositely bevelled surfaces arranged to bear against the longitudinal edges of the flap during the effective motion of said element, and including also an intermediate depending member which coincidentally bears upon the body of the flap.

4. In tucking means for the cover flaps of match books, a tucking element having flap positioning members for acting upon the longitudinal edges of the flap during the effective motion of said element.

5. In tucking means for the cover flaps of match books, a tucking element having flap positioning members for acting upon the longitudinal edges of the flap during the effective motion of said element, said members comprising depending blocks of yieldable material having oppositely bevelled acting surfaces.

CHARLES F. WRIGHT.
